BOOKHOLDER

Robert Nelson, Arlington, and Gustof Johnson,
Jamaica Plain, Mass.

Application June 13, 1932. Serial No. 616,873

2 Claims. (Cl. 120—28)

This invention relates to bookholders for use, for instance, by stenographers to hold their notebooks during transcription. The object of the invention is to provide an efficient and inexpensive device for such a use or similar uses.

The invention will be understood by reference to the following description taken in connection with the accompanying drawing, wherein:—

Fig. 1 is a side elevation of the book holder with a book in position thereon;

Fig. 2 is a plan, the book being omitted;

Fig. 3 is a section on the line 3—3 of Fig. 1; and

Fig. 4 is an end view as seen from the right of Figs. 1 and 2.

In the example of our invention herein illustrated we have shown a holder adapted for use with a book of the end-opening type having a stiff cover although not so limited. The holder is preferably constructed from sheet metal bent into the general form of an easel and having a body portion to underlie the book, herein shown as constructed from two overlapping parts 5 and 7 which may be adjustably joined together as by means of the slots 9 in one receiving the bolts 11 carried by the other, this permitting the width of the body portion to be adjusted as desired, the parts being held clamped in adjusted position by means of the wing nuts 13. The central parts 30 of the lateral portions of the two pieces may be bent downwardly to form the supporting feet 15 which may be shaped as shown in Fig. 1 to support the body at a desired inclination. The lower or rear end of part 5 may be bent upwardly to provide a flange 17 forming a ledge or support for the book.

Suitable means are provided for positioning the book on the holder and desirably arranged to hold the leaves against casual turning while permitting intentional manipulation thereof. Herein the lateral portions of the two pieces of metal adjacent the feet 17 at either end thereof are bent upwardly to provide suitable elements for such purpose. Considering first the lower end of the holder, in the preferred form herein disclosed we have shown a portion 19 of the member 7 bent over abruptly to provide a flange overhanging the body portion substantially parallel thereto, beneath which a corner of the cover c of the book 50 may be tucked and preventing the book from being tipped off the holder as might occur, for example, in cases where it extends beyond the upper end thereof as shown in Fig. 1 by pressure on the projecting end. Opposite the part 17 a portion 21 of the member 5 is bent upwardly to provide a relatively gently sloping flange overhanging the leaves of the book so that they will not casually be lifted from beneath the same, yet can be readily moved up past the edge of the flange when desired.

At the upper end of the holder the lateral portions of the metal parts are bent upwardly to provide the upwardly projecting arms 23 which at a suitable distance about the surface of the body portion of the holder are bent inwardly at 25 to provide a relatively restricted throat and preferably flare outwardly above the same, as best shown in Fig. 3. The holder being of the proper size or properly adjusted for the book with which it is to be used, this throat, that is, the distance between the portions 25, is somewhat narrower than the book. The upper cover of the book and any leaves which precede that about to be referred to may be passed from rear to front between the two arms beneath throat 25 in first positioning the book on the holder. The narrow throat prevents the leaves from lifting upwardly and at the same time leaves may be lifted from the lower position and swung downwardly through the throat, their flexibility 75 permitting them to pass in this manner.

We are aware that the invention may be embodied in other specific forms without departing from the spirit or essential attributes thereof, and we therefore desire the present embodiment to be considered in all respects as illustrative and not restrictive; reference being had to the appended claims rather than to the foregoing description to indicate the scope of the invention.

We claim

1. A bookholder comprising a pair of sheet metal sections having portions overlapping and adjustably slidably joined to provide a central body of variable width, said portions having downwardly extending flanges supporting said body at an inclination and adjacent flanges at the upper end of said body slightly overhanging the same, and means at the lower end for supporting the book.

2. A bookholder comprising a body to underlie the parts of an end-opening book having means for supporting the same at an angle, an abruptly overhanging flange at a lower corner thereof for retaining the book cover, a gently sloping flange at an opposite corner to retain leaves against said cover while permitting them to be intentionally raised past the same by flexure thereof and a pair of lateral arms at the upper end of the body overhanging the same defining a restricted throat beneath which the opposed cover may be slid from below and adapted to retain the same against upward movement therethrough and permitting a leaf to fold downwardly through the same on flexure thereof and serving to retain such leaf against unintended release.

ROBERT NELSON.
GUSTOF JOHNSON.
